BAG AND SUPPORT THEREFOR

Fred A. Krohm, Hobart, Ind., assignor to The Anderson Company, a corporation of Indiana

Application January 8, 1954, Serial No. 402,871

4 Claims. (Cl. 248—95)

This invention relates generally to supports and more particularly is directed to a device for supporting a container.

The device may be used wherever applicable but is preferably utilized to support a bag for containing a liquid adapted to be projected onto a windshield to assist the wiper in cleaning the windshield. The device may be mounted where desired but is preferably connected to the front side of the fire wall at the rear of the engine of an automotive vehicle to serve as a reservoir for the liquid that is to be squirted on the windshield.

More specifically, an object of the invention is to provide a novel supporting assembly comprising a bracket and a pair of hooks which serve to resiliently support a bag in a particular manner.

Another object of the invention is to provide a supporting assembly in which the hooks are secured to the bracket for limited pivotal movement and so that the bag will be held in a predetermined upright position to prevent collapse of the bag.

A particular object of the invention is to provide a supporting assembly of the character just referred to in which the hooks may be pivoted to positions to place the supporting assembly in a collapsed compact condition to facilitate packaging.

A further object of the invention is to provide a bag formed with elongated pockets therein which are adapted to detachably receive portions of the hooks above referred to.

A still further object of the invention is to provide a bag which is reinforced at appropriate locations so that it will withstand torsional strains.

Another object is to provide a bag having a novel valve assembly and filter therein.

Many other objects and advantages of the inventions will become apparent after the description hereinafter set forth is considered in conjunction with the drawings annexed hereto.

In the drawings:

Figure 1 is a perspective view of a bag supported on the hooks of the bracket assembly with portions of the structure broken away to indicate details of construction;

Figure 2 is an enlarged partial vertical section showing the manner of securing a closure assembly to the bag;

Figure 3 is an enlarged perspective view showing the manner in which each of the hooks is connected to the bracket;

Figure 4 is an enlarged partial vertical section taken through the valve and filter assembly;

Figure 5 is a transverse section taken through the structure illustrated in Figure 4 showing the character of the valve seat;

Figure 6 is an enlarged vertical section taken through the structure of Figure 4 showing the relationship of a valve in the form of a ball which is operatively related to the valve seat;

Figure 7 is a partial vertical section taken through a

2

part of the structure of Figure 4 showing the detail of the valve seat; and

Figure 8 is a partial top view of the supporting assembly showing the manner in which one of the pair of hooks may be pivoted to an inoperative position to place the supporting assembly in a collapsed condition for packaging.

Referring more particularly to the drawings, number 1 generally designates a bag for liquid and 2 designates a supporting assembly comprised of an elongated bracket 3 and a pair of corresponding generally U-shaped flexible hooks 4.

The bag is substantially of a one-piece construction and is preferably made by folding a length of a fabric to provide a fold at its upper edge. The fabric is impregnated with a suitable plastic material so as to render the bag waterproof and at the same time afford a means whereby the lapped portions of the material can be bonded or united by the application of heat and pressure to form a bottom groove 5, parallel side grooves 6, and top grooves 7. The bag is provided with side wing portions and longitudinal edge portions of the wings are bonded together to provide grooves 8 which are disposed in parallel relation to the side grooves 6. The outer upper and outer lower corners of the wings are preferably bonded together over a greater area as indicated at 9 and 10 so as to reinforce the wings. The side grooves and the grooves in the wings are spaced apart so as to provide a pair of parallel pockets 11 which are adapted to detachably receive leg portions of the hooks above referred to.

The bracket is preferably elongated and provided with offset end extremities which carry the hooks. The supporting assembly may be secured to any part of the vehicle such as the fire wall as stated above in any manner desired, but as herein shown an intermediate flat portion 12 of the bracket is provided with a pair of holes 13 through which fastening means may be extended for securing the assembly in place.

Each offset extremity of the bracket is provided with a relatively long front corrugation 14 and with a rearwardly extending shorter corrugation 15 which in combination serve to provide receiving or attaching means through which a rear leg 16 of a hook extends to support the hook for pivotal movement with respect to the bracket. Each extremity of the bracket is preferably provided with a rearwardly extending depression which forms a recess 17 located adjacent the upper end of the front corrugation as clearly shown in Figure 3. As a result of providing the depression a shoulder is formed on each offset to provide a stop 18. Each hook also includes a front leg 19 which is of a greater length than the rear leg so that the upper end of the front leg will extend upwardly above the bracket. The front legs of the hooks are adapted to be inserted into the pockets 11 of the bag as clearly illustrated and the upper end of each front leg is preferably provided with a loop 20 so as to prevent said ends from poking or wearing holes through the upper folded edge portions of the bag.

The hooks are connected to the bracket by merely inserting the rear short legs through the corrugations constituting the receiving or attaching means and then bending their free ends to provide offsets 21 which are adapted to respectively normally nest in the recesses 17 and engage the base portions thereof as clearly illustrated to limit inward movement of the front legs of the hooks to substantially right angular positions with respect to the bracket so that the bag when supported on the hooks will be maintained in a stabilized position in spaced-apart relation to the inner legs of the hooks including the offset end extremities of the bracket to prevent the bag from chafing or otherwise rubbing thereagainst. It

will be noted that the offset ends 21 of the rear legs of the hooks normally point toward one another and rest upon the stops 18 to prevent downward movement of the hooks with respect to the bracket. Pivoting the hooks as described facilitates insertion of their front legs into the pockets of the bag and also offers advantages with respect to packaging because the hooks can be pivoted to the position exemplified in Figure 8 to place the supporting assembly in a compact collapsed condition. To place the assembly in this condition, it is merely necessary to push upwardly on the hooks so that the offsets 21 on the upper ends of the rear legs of the hooks are moved out of the recesses and above the upper edge of the bracket whereupon the hooks are pivoted so that the front legs thereof engage the bracket as shown in Figure 8. If desired, the hooks may be pivoted so that the front legs will engage the rear side of the bracket to place the supporting assembly in a different collapsed condition.

It will be noted that when the bag is properly supported as illustrated in Figure 1 it is held in a stabilized balanced position due to the location of the hooks and their points of connection with the bracket. The hooks, as pointed out above, serve to resiliently support the bag and due to the operative relationship between the hooks and the pockets of the bag the hooks and pockets will serve to alleviate any excessive torsional strains produced by the weight of the liquid in the bag and at the same time afford means whereby the bag is suspended against excessive side play or wobble. It will also be noted that the lower extremity of the bag extends below the lower ends of the hooks and as a consequence the lower extremity is held in a more relaxed state or condition than that portion of the bag located between the front legs of the hooks. The purpose of this will be subsequently described.

The bag is preferably provided with a tubular neck 22 which is permanently secured and sealed within a tubular portion 23 of the bag as illustrated in Figures 1 and 2. A closure or cap 24 is detachably secured to the neck and this is preferably accomplished by providing the upper end of the neck with a lip 25 and the cap with a tapered flange 26 of a size whereby the cap may be pressed onto the neck so that the lip will engage the inner cover surface of the cap and the free edge of the flange will intimately circumferentially engage the exterior surface of the neck at a location spaced longitudinally from the lip to provide a fluid-type connection between the neck and lip.

The cap is preferably provided with an integral upper tubular extension 27 and a lower tubular extension 28. A conduit 29 is adapted to be fastened to the upper extension 27 for communicatively connecting the bag with components of a washer system. A flexible tube 30 is connected to the lower extension 28 as clearly illustrated and the lower end of the tube supports a combined valve and filter assembly.

The valve and filter assembly, as clearly exemplified, includes a tubular fitting 31 which extends into the lower end of the flexible tube, a tubular element 32 secured about the fitting and a tubular member 33 which serves as a valve seat for a ball valve 34 which is movable between this seat and the lower end of the fitting 31. A cup 35 is secured to the lower end of the tubular element 32 and a filter 36 in the form of a fine meshed screen is detachably retained in the cup by a flanged ring 37 functionally held in the cup. When the washer system, not

shown, is operated one way liquid will be drawn up through the filter and unseat the valve to allow the liquid to flow through notch 38 in the fitting 31 and up through the fitting and tube. The size of the cup 35 is such that the lower portion of the bag will be slightly expanded and this expansion is permitted due to the relaxed condition of the lower portion of the bag as indicated above.

Having thus described my invention, it is obvious that various modifications may be made in the same without departing from the spirit of the invention; and, therefore, I do not wish to be understood as limiting myself to the exact form, construction, arrangement, and combination of parts herein shown and described and defined in the claims.

15 I claim:

1. An assembly of the kind described comprising a bracket and a hook, said bracket being constructed of sheet material and having a substantially planar portion deformed to provide an open-ended groove, said bracket being further deformed to provide offsets spaced from the planar portion and disposed at the ends of the groove, one of said offsets in combination with the planar portion defining a recess disposed substantially transverse to the length of the groove, said hook comprising an inner leg 20 and an outer leg joined to the inner leg and disposed in a plane substantially parallel thereto, said inner leg being mounted in and held in said groove by said offsets and having a lateral projection disposed in the recess and bearing against the adjacent offset for limiting downward movement of the hook and normally locating the outer leg in a predetermined substantially parallel relation to the said planar portion of the bracket for supporting an article.

2. The assembly defined in claim 1, in which the hook 35 may be adjusted lengthwise of the groove to release the lateral projection on the inner leg from the recess so that the hook may be pivoted to cause the outer leg to overlie the bracket and thereby effect collapse of the assembly.

40 3. An assembly comprising an elongated bracket, a pair of spaced hooks, each of said hooks having an inner leg pivotally connected to the bracket and an outer upright leg, means on the inner legs cooperating with the bracket for limiting pivotal movement of the upright 45 legs toward one another, and a container having a pair of substantially parallel inverted side pockets within which the upright legs are disposed for supporting the container and so the container serves to hold the upright legs against pivotal movement away from one another.

50 4. The assembly defined in claim 3, in which the bracket is offset intermediate the hooks so that the bag is spaced from the offset to prevent contact therewith.
